TOP FOR A FENCE POST

Bernard Youngworth, Baltimore, Md.

Application March 30, 1955, Serial No. 35,290

Term of patent 14 years

(Cl. D28—4)

I claim:

The ornamental design for a top for a fence post, as shown.
